Term of patent 14 years

(Cl. D15—1)

FIGURE 1 is a front perspective view of a chair or similar article showing my new design with portions thereof broken away to indicate indeterminate length;

The dominant features of my design reside in those portions shown in full lines.

This is a division of design application Serial No. 7,120 filed May 15, 1967.

I claim:

The ornamental design for a chair or similar article, as shown and described.
